UNITED STATES PATENT OFFICE.

GEORGES MICHOT, OF DROMARA, IRELAND, ASSIGNOR TO THE FIBRE CORPORATION LIMITED, OF LONDON, ENGLAND.

SCUTCHING MACHINE FOR FLAX AND OTHER FIBROUS MATERIALS.

Application filed July 6, 1921. Serial No. 482,821.

(GRANTED UNDER THE PROVISIONS OF THE ACT OF MARCH 3, 1921, 41 STAT. L., 1313.)

To all whom it may concern:

Be it known that I, GEORGES MICHOT, a citizen of the Swiss Republic, and residing at Dromara, County Down, Ireland, have invented certain new and useful Improvements in Scutching Machines for Flax and Other Fibrous Materials (for which I have filed application in Great Britain, No. 7,806, dated 16th March, 1920; India, filed 3d 10 January, 1921; South Africa, filed 23d December, 1920), of which the following is a specification.

This invention relates to machines for scutching flax and other fibrous materials 15 of the type in which the fibrous materials are gripped between two superposed conveying bands which, by means of suitable guide pulleys, convey the said material into and past the zone of action of the scutching 20 blades or beaters, and the scutching heads are arranged at a lower level than the points of feeding and withdrawal of the materials.

The object of the present invention is to 25 provide an improved scutching machine which can be more conveniently operated, thereby facilitating increased output.

The invention consists in a scutching machine of the type referred to comprising a 30 casing within which the beaters are practically enclosed, and means for exhausting air from inside the casing, preferably with an air duct below the ground level.

The invention also consists in means for 35 mounting and tensioning the conveying bands, comprising a pair of carrier pulleys in convenient proximity to the scutching heads, and a pair of guide pulleys, round which the conveying bands pass two jockey 40 pulleys independently mounted one vertically above the other, one for each conveying band, and means for exerting pressure between the jockey pulleys and their respective conveying bands.

The invention also consists in means for 45 continuously driving the conveying bands, comprising a reduction gear, and a variable speed gear which can be varied while the machine is running.

50 In the preferred form of carrying the in-

vention into effect, the scutching heads are arranged only on one side of the machine, the flax fibres are gripped at or towards one end thereof, and after passage through the machine and withdrawal therefrom, the flax 55 fibres are reversed and again passed through the machine or through another machine of the same kind in order that the ends previously gripped between the conveying bands may be operated on by the 60 scutching blades. In this form, the stock or frame on which the conveyor bands and pulleys are mounted is made separate from the base plate on which it is carried, and can be adjusted laterally relative to the 65 scutching heads while the machine is running. The said scutching heads are carried on shafts mounted in fixed independent bearings.

Accordingly, the invention also consists 70 in means for adjusting the stock and conveyor bands laterally relative to the scutching heads while the machine is running.

The invention also consists in providing 75 the carrier pulleys, at the flanges thereof adjacent to the scutching blades, with distributing teeth inclined in such manner as to avoid or reduce to a minimum interference with the fibres as they are being withdrawn from the carrier pulleys.

I append drawings illustrating my invention as carried into effect in one form:—

Figure 1 is an elevation;

Figure 2 a plan, and

Figure 3 a transverse section through the 85 axes of the belt conveyor pulleys;

Figure 4 is a plan partly in section illustrating the preferred form of variable speed and reduction gear for driving the belt conveyor.

The scutching wheels 1 are mounted on two horizontal shafts 2 above but near the ground or platform 3 on which the operator stands. The scutching blades 4 or beaters may be of wood or of suitable metal, or of 95 wood sheathed with metal. The carrier pulleys 5 which present the fibres to the scutching wheels are mounted at about the same level as the latter. A pair of guide pulleys 6 of small diameter are mounted 100

above the carrying pulleys, fairly close together in such position as to provide a large angle of contact of the conveyor bands with the carrying pulleys. The two conveying bands 7 and 8 are superposed one on the other while passing round the said carrier and guide pulleys. A jockey pulley 9 is suitably mounted a convenient distance above the guide pulleys 6, and round this 5 the inner conveying band 7 passes. Another jockey pulley 10 is mounted at a convenient distance vertically above the first-mentioned jockey pulley, and round this the outer conveying band 8 passes. The fibres 10 are fed in between the two conveyor bands at 12 on the descending side, and are withdrawn at 14 on the ascending side between the two jockey pulleys. A central vertical plate 15 is inserted between the guide pulleys to prevent interference between the ascending and descending fibres. Practically constant upward pressures are maintained 15 by the two jockey pulleys against their respective conveyor bands. For this purpose, 20 in one arrangement the jockey pulleys are each mounted on the end of a lever 16 pivoted to the frame at 18 and having towards its other end a weight 20 which may be adjusted in position along the lever, so that 25 the pressure on the conveying band may be adjusted to any desired value.

Each carrier pulley 5 is provided, on the side presented towards the scutching wheel, with distributing teeth 21 projecting beyond 30 the periphery with which the conveyor band makes contact, as and for the purpose described in United States Patent No. 1,331,659. In the present invention these teeth are inclined in such manner as to be 35 approximately parallel to the conveyor band after it has left each carrier pulley, thus avoiding or reducing to a minimum 40 interference with the fibres while being withdrawn from the carrier pulleys.

One of the carrier pulleys is driven preferably from one of the shafts 2 on which the scutching wheels are mounted. The driving means comprise a reduction gear and a 45 variable speed gear, the latter providing means for adjusting the rate of travel of the conveyor bands in relation to the speed of rotation of the scutching wheels. One suitable form of the said driving means is a variable speed friction gear 22, 23 of the disc- 50 and-wheel type, in combination with a worm wheel reduction gear 24, 25. Another and preferable form is a variable speed gear of the type comprising a belt 26 and a pair of conical pulleys 27, in combination with an 55 epicyclic reduction gear. The epicyclic gear illustrated comprises a pinion 28 fastened to the shaft, a coaxial pinion 29 fixed to the bearing and double planet pinions 30 mounted on the pulley 27.

60 The stock or frame S on which the con-

veyor band and pulleys are mounted is preferably made separate from the frame or bed-plate F, and means, such as adjusting screws 32, are provided for relative lateral adjustment, whereby the overhang of the 70 fibres projecting from the conveyor bands into the paths of the scutching blades may be adjusted while the machine is running.

The scutching wheels are enclosed as completely as is practicable within a casing 33, 75 which is in communication with an exhaust fan. The fibres while being operated on by the scutching blades depend from the conveyor bands through an opening into the said casing, a draught of air enters the opening and the loose material removed from the fibres is prevented from polluting the atmosphere. Provision is made for intercepting the said loose material, and for periodically removing it from the casing or from the 85 chambers or ducts in communication therewith. The ducts between the casing and the exhaust fan are preferably underground, or below the floor on which the machine rests.

Claims.

1. In a scutching machine of the type in which the material is conveyed between a pair of superposed endless bands in a plane parallel to and close to the plane of motion of the beaters, and the beater shafts are arranged at a lower level than the places of feeding and withdrawing material, means for mounting and tensioning the conveying bands comprising a pair of carrier pulleys mounted at about the same level as the beater shafts, a pair of guide pulleys around which the conveying bands with the material pass, two jockey pulleys, one for each conveying band independently mounted, one vertically above the other, and means for exerting 10 pressure between the jockey pulleys and their respective conveying bands.

2. In a scutching machine as claimed in claim 1, a stock, and means for adjusting the stock and conveying bands laterally relatively to the beaters while the machine is running.

3. In a scutching machine as claimed in claim 1, flanges arranged on the carrier pulleys adjacent to the beaters and provided with distributing teeth, inclined in such manner as to permit the fibers to move easily away therefrom as the superposed conveyor bands leave the carrier pulleys.

4. In a scutching machine as claimed in claim 1, means for continuously driving the conveying bands comprising a reduction gear and variable speed gear between one of the beater shafts and one of the carrier pulleys.

5. In a scutching machine, a pair of beater shafts, beaters mounted on said shafts, a stock arranged between said shafts, a pair of carrier pulleys located between said shafts, jockey pulleys mounted above 13

said carrier pulleys and arranged one above the other, an endless band passing around the lower one of the jockey pulleys and engaging said carrier pulleys, another endless band passing over the upper one of the jockey pulleys and superposed on the band arranged on the carrier pulleys, and means for exerting pressure between the jockey pulleys and their respective conveying bands. ¹⁰

In testimony whereof I have signed my name to this specification.

GEORGES MICHOT.
